(57) **CLAIM**

The ornamental design for a round table, as shown and described.

DESCRIPTION

FIG. 1 is a front elevation view of a round table showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a front perspective view thereof;

FIG. 8 is a back perspective view thereof; and,

FIG. 9 is an enlarged view of the encircled portion in FIG. 8.

The dash-dot lines in FIG. 8 and FIG. 9 illustrate the boundaries of the enlarged view indicators and form no part of the claimed design.

1 Claim, 9 Drawing Sheets
